CIGARETTE MAKING MACHINE

Elmer F. Oetinger, Buffalo, N. Y.

Application February 26, 1945; Serial No. 579,697

4 Claims. (Cl. 131—21)

1

This invention relates to certain new and useful improvements in machines or devices for making cigarettes.

It has for one of its objects to provide a cigarette making machine which has been primarily designed for domestic use, whereby individuals can easily and expeditiously make cigarettes for their own use.

Another object of the invention is to provide a portable machine of this character which is simple, compact and inexpensive in construction, which is reliable in operation, and which embodies effective means for charging and uniformly tamping the tobacco in a paper tube or wrapper and for finally ejecting the finished cigarette from the machine.

A further object is to provide a motor-driven cigarette-making machine having means for automatically cutting off the motor and stopping operation of the machine upon the completion of its making a cigarette.

A still further object is to provide the machine with releasable means for retaining the wrapper or tube in place during the tobacco-charging operation and at a predetermined time automatically releasing such retaining means to free the finished cigarette for ejection from the machine.

Other features of the invention reside in the construction and arrangement of parts herein-after described and particularly pointed out in the appended claims.

In the accompanying drawings:

Figure 1 is a side elevation of the cigarette making machine embodying my invention. Figure 2 is a front end view thereof. Figure 3 is an enlarged vertical section of the machine taken in the plane of line 3—3, Figure 2. Figure 4 is a cross section taken on line 4—4, Figure 3. Figure 5 is a fragmentary horizontal section taken on line 5—5, Figure 3, with the parts in their depressed position.

Similar characters of reference indicate corresponding parts throughout the several views.

In the preferred embodiment of my invention shown in the drawings, the same comprises a frame or housing 10 of substantially the shape shown, and having at one side thereof a cover plate 11. The frame supports and houses the various working parts of the machine, which is compact, light and portable and may be supported on a table or the like and detachably clamped thereto when it is desired to make a batch of cigarettes. An electric motor 12 is mounted at one side and adjacent the rear end of the frame, while a substantially funnel-shaped

2

hopper 13 is mounted at the upper front or operating end of the machine to receive a supply of tobacco and leading from the lower end thereof is a tubular discharge spout 14 on which a pre-formed cigarette wrapper 15 is removably supported in telescoped relation therewith to receive a charge of tobacco and thereafter be ejected therefrom as a finished product ready for smoking. As shown, the front or operating end of the frame is preferably inclined at a convenient angle to the vertical.

Guided in the upper front end of the frame 10 for operation in the adjoining side of the hopper and its discharge spout 14 is a reciprocating tobacco feed plunger 16 which serves to agitate as well as direct and tamp the tobacco into the cigarette wrapper, and which further functions, at a predetermined time in the charging operation, to gradually force the charged wrapper 15 axially in a step by step fashion from the discharge spout. This plunger is preferably tapered, as shown, to properly effect the free feed of the tobacco into the wrapper and is provided on its operating face with serrations 17 forming downwardly-facing shoulders which intercept portions of the tobacco and force it downwardly into the wrapper. Uniform motion is transmitted to the plunger by any suitable means, for example, by an eccentric 18 fixed on a shaft 19 journaled in the frame 10 and driven from the electric motor 12 by a belt and pulley drive 20, and by a vertically-swinging, eccentric-engaging strap or lever 21 fulcrumed at one end to a pivot 22 and connected at its other end by a link 23 to an extension 24 of the plunger. The strap-pivot is preferably adjustable to raise or lower the operating stroke of the plunger, when working with wet or dry tobacco, respectively, and for this purpose such pivot is guided in an arcuate slot 25 in the side wall of the frame and secured in an adjusted position therein by clamping nuts 26 applied to the threaded outer end of such part. The strap 21 has a rearward extension 27 which extends through a vertical slot 28 in the rear end of the casing and serves as a handle for manually shifting the strap to the adjusted position desired. For dry tobacco, the plunger 16, through the adjustment of the strap-pivot is set in its lowest position and for wet tobacco it is set in its highest position. By adjusting the strap in this manner, the user is enabled to obtain a uniformly packed cigarette, whether the tobacco be wet or dry.

For the purpose of effectually holding the tubular wrapper 15 in telescoped relation on the

discharge spout 14 during the initial tobacco-charging operation, I provide a releasable retaining or clamping member 29 which is suitably guided for horizontal movement on the frame 10 and has a spring 30 connected thereto for normally urging such member outwardly or into clamping engagement with the wrapper. This spring may be attached to a bolt 31 for readily effecting its adjustment to the retaining pressure desired. A pendant arm 32 pivoted at 33 to the frame and joined at 34 to this wrapper-retaining member serves, when displaced inwardly in the manner presently to be described, to withdraw such member from its wrapper-retaining position, as shown by dotted lines in Figure 3, to free the wrapper for downward displacement on the discharge spout during the final charging operation, the plunger 16 acting on the tobacco then contained in the wrapper to effect such displacement.

Disposed in spaced axial relation below the discharge spout 14 for abutting engagement with the lower end of the cigarette wrapper during the charging operation is a depressible pad or member 35 formed at the free end of a vertically-swinging lever 36 pivoted at 37 in the lower portion of the frame and extending intermediate its ends through a slot 36a in the housing 10. This lever is normally retained in its upper position, shown by full lines in Figure 3, by a latch 38 fixedly applied thereto and engaging a notch 39 in the lower outer edge of the pendant arm 32. That edge 40 of this arm leading downwardly from its notch functions as a cam so that when the lever 36 is depressed in step by step fashion by the action of the plunger and the intervening tobacco core in the partially-filled wrapper, it is released from such notch and the latch thereupon acts against the cam-like edge 40 to rock the pendant arm 32 inwardly to release the retaining member 29 from clamping relation with the cigarette wrapper. During the initial stage of the charging operation, the tobacco core, in the open-ended wrapper shown, may project slightly downwardly beyond the wrapper. As the plunger continues its reciprocating movement, it tamps the tobacco in the wrapper and as the latter is filled it is intermittently forced downwardly with the lever 36 moving jointly therewith. When the wrapper is filled, this lever is in its lower position shown by dotted lines in Figure 3, and the upper end of the cigarette wrapper is substantially in registration with the lower end of the discharge spout and in such position as to be readily removed by hand from the machine.

Included in the circuit of the motor 12 is a cut-off switch 41 which is adapted to be automatically opened to stop the machine when the lever 36 reaches its lower position and the cigarette is completed. For this purpose this depressible lever has a projection 42 thereon, preferably of insulating material, which is adapted to enter between the switch-contacts to break the motor circuit, when the lever reaches the position shown by dotted lines in Figure 3. After removing a completed cigarette, an empty wrapper is telescoped on the discharge spout 14 and the lever 36 is manually swung to its initial raised position, which causes the switch 41 to automatically close and start the motor for making another cigarette.

If desired, the motor may be eliminated and the operating shaft 19 be turned by hand by providing it with a suitable crank handle.

While manifestly simple, compact and inex-

pensive in construction, this machine is so designed as to expeditiously make cigarettes of uniform quality and it is easy to operate and not liable to get out of order.

I claim as my invention:

1. A cigarette making machine, comprising a tobacco-receiving hopper having a cylindrical discharge spout adapted to removably support a tubular wrapper in communicating relation thereto, a reciprocating feed plunger operable in said hopper and its spout for tamping the tobacco into said wrapper and for simultaneously forcing the latter, as it is charged, from the spout, means for releasably retaining the wrapper on said spout during the initial tobacco-charging operation, a depressible member normally disposed in engagement with the lower end of the wrapper to form a closure therefor and adapted to be depressed during the final charging operation, and an operative connection between said depressible member and said retaining means for releasing the latter from said wrapper during such final charging operation, whereby the cigarette is gradually lowered in step by step fashion relative to the spout, said depressible member being substantially in axial alignment at all times with said spout.
2. A cigarette making machine, comprising a tobacco-receiving hopper having a discharge spout adapted to removably support the upper end of a tubular wrapper in telescoped relation thereto, a depressible member disposed in axially-spaced relation below said spout and at all times substantially axially aligned therewith and against which the lower end of the wrapper is adapted to abut, a reciprocating plunger operable in said hopper and its spout for tamping the tobacco into said wrapper and for simultaneously displacing the latter, at a predetermined time in the charging operation, from the spout in a step by step fashion, the depressible member being depressed during the displacement of the wrapper from the spout, and means operatively connected to such member and normally disposed in engagement with the wrapper to retain it on the spout, said retaining means being released from the wrapper when the depressible member is actuated in response to the movement of the tobacco thereagainst.
3. A cigarette making machine, comprising a tobacco-receiving hopper having a discharge spout adapted to removably support the upper end of a tubular wrapper in telescoped relation thereto, a reciprocating plunger operable in said hopper and its spout for tamping the tobacco into said wrapper and for simultaneously displacing the latter, at a predetermined time in the charging operation, from the spout in step by step fashion, a releasable gripping element engageable with the wrapper for retaining it on the spout during the initial charging operation, an electric motor including a control switch for transmitting motion to said plunger, and a depressible member operatively connected to said gripping element and said switch and disposed in the lowering path of travel of the tobacco for actuation thereby to cause, at predetermined times, the movement of the gripping element to its released position and the movement of the switch to its open position.
4. A cigarette making machine, comprising a tobacco-receiving hopper having a discharge spout adapted to removably support the upper end of a tubular wrapper in telescoped relation

thereto, a compressible member disposed in axially-spaced relation below said spout and against which member the lower end of the wrapper is adapted to abut and which member is adapted to be depressed as the wrapper is charged with tobacco, a reciprocating plunger operable in said hopper and its spout for tamping the tobacco into said wrapper and for simultaneously displacing the latter, at a predetermined time in the charging operation, from the spout in step by step fashion, means for transmitting motion to said plunger including an electric motor having a control switch therefor, and means operatively connecting said compressible member with said switch to effect its automatic opening when such member reaches its wrapper-charged, depressed position.
